[57] CLAIM

The ornamental design for a water closet seal, as shown and described.

DESCRIPTION

FIG. 1 is an elevational view taken from one side of a water closet seal showing my new design, the opposite side being identical to the side shown;

FIG. 2 is an elevational view taken from one end thereof, the opposite end being identical to the end shown;

FIG. 3 is a top plan view thereof;

FIG. 4 is a bottom view thereof; and,

FIG. 5 is a perspective view thereof.
